Primary Examiner — Cynthia R Underwood(74) *Attorney, Agent, or Firm* — Additon, Higgins & Pendleton, P.A.(57) **CLAIM**

The ornamental design for an electronic device enclosure, as shown and described.

DESCRIPTION

FIG. 1 is a perspective view of an electronic device enclosure in accordance with the present invention;

FIG. 2 is a rear view of the electronic device enclosure of FIG. 1;

FIG. 3 is a front view of the electronic device enclosure of FIG. 1;

FIG. 4 is a right side view of the electronic device enclosure of FIG. 1;

FIG. 5 is a left side view of the electronic device enclosure of FIG. 1;

FIG. 6 is a top plan view of the electronic device enclosure of FIG. 1; and,

FIG. 7 is a bottom plan view of the electronic device enclosure of FIG. 1.

The broken lines represent portions of the structure that forms no part of the claim. The dot-dash-dot lines represent a boundary of the claim and form no part of the claim.
